US0D1068903S

(12) **United States Design Patent** (10) Patent No.: **US D1,068,903 S**
(45) Date of Patent: ** Apr. 1, 2025

(54) **CAMERA**

(71) Applicant: **GoPro, Inc.**, San Mateo, CA (US)

(72) Inventors: **Huy Phuong Nguyen**, Alpine, UT (US); **Daniel J. Coster**, Oakura (NZ); **John George Muhlenkamp, IV**, Mapleton, UT (US); **Heman Au**, Seattle, WA (US); **Senka Agic Bergman**, Montara, CA (US); **Nicholas Vitale**, Foster City, CA (US)

(73) Assignee: **GoPro, Inc.**, San Mateo, CA (US)

(**) Term: **15 Years**

(21) Appl. No.: **29/975,011**

(22) Filed: **Nov. 26, 2024**

Related U.S. Application Data

(63) Continuation of application No. 29/891,972, filed on May 11, 2023, now Pat. No. Des. 1,058,641, which is a continuation of application No. 29/765,706, filed on Jan. 11, 2021, now Pat. No. Des. 990,540, which is a continuation of application No. 29/661,818, filed on Aug. 31, 2018, now Pat. No. Des. 907,680.
